BOILER FEED PUMP

Filed Sept. 4, 1924

UNITED STATES PATENT OFFICE

RAYMOND E. WHITE, OF NEWTON, MASSACHUSETTS, ASSIGNEE TO STEAM VEHICLE CORPORATION OF AMERICA, OF NEWTON, MASSACHUSETTS, A CORPORATION OF NEW YORK

BOILER FEED PUMP

Application filed September 4, 1924. Serial No. 735,891.

My invention has reference to boiler feed devices or pumps, and more particularly to driving means for such pumps as used on steam power units, for example, steam-driven vehicles or automobiles.

Heretofore, it has been customary in the operation or driving of steam-driven cars to drive the water pumps by means of a take-off from the engine or crank shaft, in the form of a reciprocating rod, and at times when the speed of the engine and drive shaft is not sufficient to operate the pump in accordance with or in proper proportion to the steam demand, as when the vehicle is negotiating a very steep, long grade at a slow rate of speed and the steam demand is excessive, insufficient water would be pumped to the boiler to meet this demand, thus requiring external assistance, such as hand pumping, to make up the deficiency.

It is the object of the present invention to overcome this difficulty by insuring proper operation of the pump and a supply of water to the boiler to meet the demand of steam used or required for driving or power purposes at all times, even though the speed of the vehicle drops below a certain point, as when traveling up hill, or over mountain or rough roads, thus obviating the necessity for manual or hand pumping when the steam demand is greatest.

The invention also comprehends a novel take-off device by which the water pump may be driven from a drive shaft operated as a take-off from the engine crank shaft, which drive shaft also serves to operate a generator which, through the medium of a manually or automatically operated declutching device, may be set in operation to drive the water pump when the speed of the vehicle drops below a critical point as when negotiating a steep grade at a slow rate of speed, at which time the steam demand is the greatest, thereby obviating the necessity for manual operation of the pump and causing

the generator to operate as a motor and to keep the boiler feed pump up to the proper speed according to the demand on the boiler. This is very desirable for mountain driving or for pumping when the vehicle is standing at rest.

The invention therefore embodies novel means for automatically or manually throwing into operation a generator, storage battery or other reserve source of driving means, which generator may be ordinarily driven from the motive or power source of the vehicle, but which when the latter is not capable of driving the water pump at sufficient speed to meet the demand for power and supply of water required by the steam generating source, such reserve force will become effective, thereby insuring a supply of water to the boiler to meet the demand and maintaining efficient operation and maximum driving power.

With the above and other objects in view, the invention consists in certain novel combinations, and arrangements of parts to be hereinafter more fully described in claims.

In the drawings the figure is a fragmentary plan view showing an automobile chassis equipped with the driving or power unit, including the water pump operating means constituting the subject matter of the present invention.

Referring to the drawings in detail, in which the invention is shown applied to a motor vehicle or automobile such as a permanently geared engine to axle type to which the pumping system is desirably applied, 10 designates the chassis or frame, 11 the rear axle housing having the usual rear axle bearing the driving wheels 12, which parts may be of conventional construction. The motor 85 is designated at 13, being in the form of a steam engine provided with the steam inlet pipe or conduit 14, and the exhaust pipe 15, the former being connected to the boiler or steam generator, and the latter to the con- 90

tainer 16 as shown. The engine is supported by the spring suspension 17 from the side bars of the frame or chassis, and the controlling devices for the engine and wheel brakes designated at 18 and 19 may be mounted in any preferred or well known manner as upon the transverse supporting rods or shafts 20, or arranged to operate the same in the conventional or well known manner or in any special manner desired.

The engine casing is provided with a crank case 21 at the rear end thereof, connected with the axle housing 11, having a supplemental casing 22 at one side in which the engine shaft is geared or otherwise operatively connected to a drive shaft 23 extending alongside the engine and casing thereof, and preferably provided within the ball bearing means 24 carried by a cross member 25 of the frame extending between the side bars 10. Fabric universal joints or the like 26 may also be inserted in the length of the shaft 23 adjacent the ends or bearing points thereof, to allow for the necessary angular movements during up and down movements of the rear wheels and axle with respect to the frame of the machine. It may also be mentioned that the casing 22 provides a gear box in line with the crank shaft whereby through the medium of suitable driving means such as miter gears, rotation may be imparted to the shaft 23 from the engine.

In the drawing I have illustrated somewhat diagrammatically a clutch 27. This clutch may be of any suitable type well known in the art. It may be either manually controlled, as by a hand lever, or it may be automatically controlled, as by the temperature or pressure of the steam in the boiler through any suitable thermal or pressure device also well known in the art.

At its forward end, the shaft 23 is connected through the medium of the suitable manually or automatically operated clutching device 27, including a spring 28 normally urging the clutch into operative engagement, with a shaft 29 in which is interposed universal joints 30 upon opposite sides of the gear take-off device 31 constituting operative geared drive connections between the interposed shaft section and the water pump 32, preferably of the double-acting four-cylinder type as illustrated. The drive connection 31 is adapted to operate the pump 32 through the medium of the crank shaft 33 thereof whereby to supply the normal or required amount of water to the boiler or other steam generating plant, not shown, in the efficient operation of the vehicle. The forward end of shaft 29 is operatively connected to a generator 34, as through the medium of a chain drive 35 around which a suitable case 36 may be mounted to render the same noiseless. It is to be understood that the generator is operating and generating current

in connection with suitable storage batteries 40 which may be used for lighting or power purposes, or for operating the water pump 32 in accordance with the present invention as will be presently pointed out. Of course, it is to be understood that suitable control means are provided for regulating the action of the generator or source of electrical energy such as storage batteries. The generator is of that type which is adapted to charge a battery as long as the voltage created thereby is above a predetermined value. As soon as the voltage created by the generator falls below this value the generator automatically ceases to charge the battery. Now in the present invention, as long as the shaft 29 is running at or above a certain speed, the voltage coming from the generator will be sufficient to charge the battery 40. If the speed of the shaft 29 falls below this certain speed the generator will automatically cease to charge the battery 40. Through the operation of the clutch 27, the shaft 23 is disconnected from the shaft 29. Then by operating a switch 41 which may be of any usual or suitable construction, the battery 40 may be made to supply current to the generator which then functions as a motor to drive the shaft 29 and the associated pump. As is well known to those versed in the electrical art, it is quite common practice to employ generators which are adapted to serve the above discussed two functions, namely, that of charging the battery until the voltage drops below a set amount and then serving as a motor utilizing current from the same battery.

In the operation of the illustrated embodiment, during the normal operation or running of the engine when the vehicle is traveling on level or even ground and the steam demand on the boiler is normal, the shaft 23 through its geared or operative drive connections with the crank shaft or engine, will be driven at the required speed for the proper operation of the water pump 32, the clutch 27 being connected to drive the shaft 29 and through the geared connection or worm gear 31, to operate the pump 32 for supplying the necessary volume of water to the boiler or steam generating plant to meet the demand upon the same by the engine. However, when the vehicle is negotiating a very steep, long grade at a slow rate of speed, or the travel of the vehicle over rough roads or surfaces is such that the speed is insufficient to operate the pump according to the speed demand, especially when the steam demand is greatest or excessive, and insufficient water would be pumped to the boiler, the present device obviates the necessity of hand-pumping to meet the requirements to overcome the deficiency. For this purpose, the clutch 27 is operated manually or automatically to operatively disconnect or declutch the shaft 23 from the shaft 29 at a time when the speed of the ve-

hicle drops below a critical point. Previous to this the generator 34 was being driven through the shafts 23 and 29, which were operatively connected at the clutch 27, thus serving to generate the current and store the energy for various uses, including the operation of the water pump 32, which operation is brought about under suitable control means 41 upon the disconnection or declutching at the point 27 of the shafts 23 and 29. This being effected, the generator would then operate as a motor to drive the water pump 32 through the medium of the shaft 29 and the worm drive or gear connections 31 between the same and the crank shaft 33, which will result in the proper feed of water to the boiler, thereby keeping the boiler feed pump up to the proper speed. This operation is especially desirable in traveling over hilly roads or grades and is effective whenever the speed of the vehicle and thus the engine and the shaft 23 driven therefrom through mitre gear connections 22 fall below normal.

It is also to be understood that the invention contemplates the application of the principles of operation herein set forth to driving means other than motor vehicles wherein the driving means becomes inoperative or incapable of performing its functions, especially in connection with an auxiliary element of the power unit or transmission system, auxiliary or storage source of energy driven by the power means during ordinary operation, is brought into play or operation to operate the pump for other auxiliary devices for supplying the required water to the boiler or steam generator plant, or otherwise, according to the requirements. By this means, efficient and maximum operation is insured and in a device such as described, maximum driving power and efficiency is insured until such time as the condition again assumes normal.

I do not intend to be limited to the details shown and described except as the same are called for in the appended claims.

I claim:—

1. In combination with an engine and a source of steam supply therefor; of a pump for supplying water to the source of steam supply normally operated by the engine, and means operable when the speed of the engine runs below a predetermined minimum to operate the pump.

2. In combination with an engine and a source of steam supply therefor; of a pump for supplying water to the source of steam supply, normally operated by the engine, power generating means operated by the engine during its normal operation and operatively connected to the pump, and means to disconnect the pump and engine whereby the pump may be operated by the last named means when the engine operating speed drops

below that required for the operation of the pump.

3. In a motor vehicle, an engine, a source of fluid supply for the engine, feeding means for said fluid supply, a take-off from the engine adapted to operate said feeding means during ordinary running and when the demand upon the engine is not excessive, and means adapted to operate the feeding means independently of the take-off from the engine at times, including when the demand upon the engine is excessive or in traveling upgrade.

4. In a motor vehicle, an engine for driving the same, a source of fluid energy for the engine, feeding means for the latter source, a gear take-off device from the engine having operative connection with the feeding means, means operative during the ordinary running of the engine and vehicle when the demand on the engine and source of energy is not excessive to store energy for operating the feeding means when the demand is excessive or in traveling upgrade, and means for disconnecting the feeding means from the gear take-off of the engine at such times, whereby the feeding means will be operated solely by the stored energy.

5. In combination with an engine and a pump adapted to be operated from the engine and having operative connection therewith, means for operating the pump independently of the engine when the demand on the engine is beyond normal, and means for disconnecting the engine from the pump at such times.

6. In combination with a steam engine having a source of steam supply and a pump for supplying water thereto, of a drive shaft operatively connecting the engine and pump for operating the latter, a clutch included in the connection adapted to disconnect the engine from the pump, and a generator operated from the shaft during the ordinary operation of the engine while also operating the pump, whereby when the engine and pump are disconnected, the pump may be operated by the generator.

7. In combination with a steam engine and a source of steam supply therefor; of a pump for supplying water thereto, a shaft having geared connection with the engine and the motor for driving the latter from the engine, a generator operated by the shaft and operatively connected to the pump, and a clutch interposed in the shaft for disconnecting the engine and pump to permit the latter to be operated by the generator independently of the engine.

8. In combination with a steam engine having a source of steam supply and a pump for supplying water thereto; of operative drive connections between the engine and the pump for operating the latter during ordinary running of the engine or when traveling on level surfaces as drive means for a vehicle,

means for storing energy from the engine operation at such times and having operative connection with the pump to operate the latter independently of the engine upon the 5 pump and engine being operatively disconnected, and means to disconnect the engine and pump.

In witness whereof, I hereunto subscribe my name this 29th day of August, 1924.
